WO	2012170690 A2	12/2012

Primary Examiner — Mark A Goodwin(74) *Attorney, Agent, or Firm* — McKee, Voorhees & Sease, PLC(57) **CLAIM**

The ornamental design for circular seed manifold, as shown and described.

DESCRIPTION

FIG. 1 is a perspective view of a seed tube module according to the present invention, and which comprise a portion or segment of a circular seed manifold.

FIG. 2 is a side elevation view of the module shown in FIG. 1, with the view being the same on all sides; and,

FIG. 3 is a top plan view of the module shown in FIG. 1. Structure, environment, and/or boundaries shown in broken lines form(s) no part of the claimed design.

Some aspects of the circular seed manifold are shown with broken lines. The appearance of any portion of the circular seed manifold in broken lines forms no part of the claimed design.

1 Claim, 3 Drawing Sheets(56)
